UNITED STATES PATENT OFFICE.

JAMES W. PENFIELD, OF WILLOUGHBY, OHIO.

BRICK-KILN.

SPECIFICATION forming part of Letters Patent No. 289,024, dated November 27, 1883.

Application filed August 14, 1883. (No mod.1.)

To all whom it may concern:

Be it known that I, JAMES W. PENFIELD, of Willoughby, in the county of Lake and State of Ohio, have invented certain new and useful Improvements in Brick-Kilns; and I do hereby declare the following to be a full, clear, and exact description of the invention, such as will enable others skilled in the art to which it pertains to make and use the same.

10 My invention relates to improvements in brick-kilns; and it consists in certain features of construction and in combination of parts hereinafter described, and pointed out in the claims.

15 The object of my invention is to provide a brick-kiln in which the heat shall be well utilized and so subject to direction and control that the bricks may be evenly and properly burned in all parts of the kiln.

20 It is well known to those skilled in the art of brick-making that with kilns heretofore in use it was difficult to prevent the bricks that were over and near the fire from being burned too much, while near the exit of the 25 heat from the kiln the bricks would usually be only partially burned. In view of these facts I have invented the kiln hereinafter described, in which the aforesaid desired results may be obtained.

30 In the drawings, Figure 1 is a front elevation of a portion of my improved kiln. Fig. 2 is a vertical cross-section. Fig. 3 is a vertical longitudinal section. Fig. 4 is a plan view of a portion of the kiln. Fig. 5 is a 35 transverse section above the floor.

The kiln is provided, in the usual manner, with an outer wall, A, inclosing the structure, and in this wall, both in front and in the rear, are built the chimneys that discharge from 40 the kiln, and hereinafter described.

B represents the furnaces or fire-boxes, separated by the grate-bars b from the ash-pits C. Between the ash-pits, and joining the outer wall in front and in the rear, are the hollow 45 walls or benches D, inclosing, respectively, the flues D', that are connected with a contiguous ash-pit by the openings d, and that discharge into the chimneys d' in the front wall. These flues D' are arched or covered, 50 so that as the walls D approach the height

of the grate-bars they are solid. Above the level of the grates these walls are not continuous or solid, but are made each of a number of narrow piers, n, running cross-wise of the respective walls, with openings l 55 between the piers, through which the heat may pass laterally from the fire-boxes, and without obstruction. These fire-boxes are arched, as shown, the arches resting upon the said piers n; but the arches themselves are 60 built solid. This construction is for the purpose of distributing the heat evenly, the solid arches above the fire-boxes confining the heat somewhat in that direction and forcing it laterally through the open spaces just described. 65 These piers n are carried to the top of the arches and beveled off, and a floor of brick or tile is laid, resting on the piers and spanning the spaces between the piers. These floor bricks or tiles are laid close together over the 70 arches, but are separated over the benches D, preferably from an inch to one and one-half inch, as shown in Figs. 2 and 5, where K represents the lower floor and L the top floor. The piers n are carried a short distance—say 75 from four to eight inches—above the lower floor, K, and a second or top floor, L, is laid in the same manner as the floor just described, and it is on this top floor that the brick, tiles, or other articles to be burned are placed. In 80 inside of the front walls, and directly over and in open relation with the respective fire-boxes, are the vertical bag-flues G, and terminating just under the arch or roof of the kiln, as shown in Fig. 3.

H are chimneys constructed in the back wall and opening into the body of the kiln a short distance above the floor.

I are small flues or openings through the top arch or roof of the kiln. The chimneys H and 90 d' and the openings I are all operated by dampers, that usually consist of a tile laid on the chimney or flue, wholly or partially closing the orifice, or removed altogether, as may be desired. Just back from under the flue G, 95 and shown in dotted lines in Fig. 3, are slight projections e in the side walls, to support large tiles that may be set crosswise of the fire-box and ash-pit, and severing the connection between the front and back parts thereof.

The operation of the device is as follows: The bricks are set in the kiln in the usual manner, and fire is made in the fire-boxes, and usually the entire length of the grate, and the 5 chimneys d' are closed on top. The heat passes partly through the floor, as already described, and partly through the flue G. If the heat were all allowed to pass through the floor and to escape at the top of the kiln, the lower portion 10 of the bricks would be burned too much and the top portion would not be burned enough. If the heat should all pass through the flues G and escape through the chimneys H, the top part of the kiln would be burned, 15 and not the bottom. By combining these two processes and allowing a part of the heat to escape in each of the two ways mentioned, the kiln may be quite evenly burned, except at the back side and near the opening into the 20 chimneys H. In order to complete the work perfectly, the fire is all drawn forward of the projections e, the uncovered grates are raked clean, the tiles placed at e, closing the back part of the fire-box and ash-pit, as aforesaid.

25 Next the openings I and the chimneys II are closed, and the chimneys d' are opened. The fire is now all in the front part of the fire-boxes, and the heat has no escape except through the flues G. After leaving the flues 30 G, the heat is deflected by the arched roof, and somewhat by the draft, and passes down mostly on the back side of the kiln and past the openings into the chimneys II, where the 35 bricks are least burned. The heat passes on down through the floors and through the exposed part of the grate-bars into the back part of the ash-pit, from thence through the opening d into the flue I', and out of the chimney d' . The direction of the hot air may be somewhat 40 changed by means of the openings d . If, for instance, the two front openings d were closed, so that the heat would be confined to the back opening, d , the heat would keep close to the back wall. If the back openings, 45 d , were closed and the front ones remained open, the heat would be drawn more or less away from the back wall and through the lower and central parts of the kiln. The product of combustion passing through the floor and 50 up through the kiln is known as the "updraft," and the said product passing through flue G to the roof and down through the kiln to the mouth of the flue II is called a "downdraft." It will be seen that with the arrangement of 55 parts both of these drafts may be in operation at the same time and from the same set of fire-boxes or furnaces, the one or the other kind

predominating according to the arrangement of dampers and the requirements of the case. For instance, first, the flue G may be closed 60 entirely and the heat all be made to pass through the floors; second, the fires may be light at the back end and heavy in front, so that the most of the heat will pass through the flue G and but little through the floors; third, by 65 drawing the fire forward and closing the fire-box and ash-pit, as aforesaid, the heat may be made to pass through the flue G and the chimney II; or the said chimney may be closed and the heat passed down through the floor and 70 out at the chimney d' . Also, by means of the dampers aforesaid, a part of the heat may escape through the chimney II and a part through the chimney d' . The two floors, or, rather, the 75 spaces between them, tend to equalize the heat, so that when one fire is hotter than another the heat will be evenly distributed through the kiln.

The term "brick-kiln" is used in this specification in its general sense, and I do not limit 80 myself to a kiln for brick alone, as it is equally well adapted to burn tiles and all products of clay.

What I claim is—

1. In a brick-kiln, the combination of two 85 floors, with air-spaces between and running crosswise and above the fire-boxes, and adapted to aid in distributing the heat evenly through the kiln, substantially as and for the purpose set forth.

2. In a brick-kiln, the combination of two floors, with air-spaces between, substantially as described, and adapted to distribute the heat by means of the unequal spaces between the floor-bricks, as set forth.

3. In a brick-kiln, the combination, with the two floors, of the piers n, constructed and arranged to form intervening spaces, l, substantially as set forth.

4. The combination, with the ash-pits C, of 100 the benches D, extending longitudinally the length of the kiln, flues I', located within the benches and communicating at one end with the chimneys d' , and lateral branch flues d , connecting the flues D' and ash-pits C, substantially as set forth.

In testimony whereof I sign this specification, in the presence of two witnesses, this 4th day of August, 1883.

JAMES W. PENFIELD.
